[57] CLAIM

The ornamental design for a cart or similar article, substantially as shown and described.

DESCRIPTION

FIG. 1 is a perspective view of a cart or similar article showing my new design;

FIG. 2 is a top plan view thereof;

FIG. 3 is a side elevational view thereof, the opposite side being a mirror image of FIG. 3; and

FIG. 4 is a front elevational view thereof, the back elevational view being a mirror image of FIG. 4.
